JAMES G. MARSHALL, OF NIAGARA FALLS, NEW YORK, ASSIGNOR TO UNION CARBIDE COMPANY, OF NIAGARA FALLS, NEW YORK, A CORPORATION OF VIRGINIA.

ELECTRODE CONTACT-CLAMP.

1,065,380.

Specification of Letters Patent. Patented June 24, 1913.

Application filed January 3, 1913. Serial No. 740,871.

To all whom it may concern:

Be it known that I, JAMES G. MARSHALL, a citizen of the United States, residing at Niagara Falls, in the county of Niagara and State of New York, have invented certain new and useful Improvements in Electrode Contact-Clamps, of which the following is a specification.

This invention relates to electrode contact clamps, the object of the invention being to provide a form of clamp which is applicable to the larger sizes of electric furnace electrodes, and provides effective contact therewith while at the same time permitting a more rapid adjustment of such electrodes within the clamp than has heretofore been possible.

It has for its further object to enable the longitudinal adjustment of electrode clamps to be effected from a distance, and to this end, a holding clamp is provided which is power-actuated, the power being preferably delivered by pneumatic, hydraulic or electric agencies, and controlled by valves or switches located at any desired point.

The invention, though capable of use where only one movable electrode is employed, is particularly designed for use in connection with electric furnaces in which a number of electrodes are used for delivering either direct, alternating or polyphase currents.

In order to avoid waste of electric power, the clamps by which current is delivered to the electrode are placed as low down as possible on the electrode, and must be raised from time to time, as the electrode wastes away and the clamps approach too close to the furnace charge. When this adjustment is effected by hand-operated devices, the operator is subjected to the heat and fumes from the furnace and it is my object to provide means for obviating this difficulty.

In the drawings,—Figure 1 is a plan; Fig. 2 is a partial elevation, one electrode only being shown; and Fig. 3 is an elevation, showing a single clamp applied to an electrode.

Referring to Fig. 1, A, A are a series of electrodes suspended by the clamping device consisting of a pair of clamping jaws G, G', hung from a support E, this clamping device being, in turn, suspended over the hearth B of the furnace, by means of the cable C. The support E is preferably made hollow, a water-cooling fluid being cir-

culated therethrough through the pipes B, R'. The jaws G, G' are also preferably made hollow and suspended from the support E in any suitable manner, but preferably by means of copper tubes H, H, through which the cooling liquid may circulate. To avoid complication of the drawing, only one pipe is shown. The jaw G is, as shown, a part of the frame H, which carries at its outer end the motor J, illustrated as a fluid-operated cylinder, whose piston is connected to the jaw G'. K, K are fluid pressure and exhaust pipes, controlled by a valve L located at any convenient point. If an electric motor is used, suitable conductors and a controlling switch will replace the pipes and valve. The motor carrying-frames H, one for each electrode, are supported from the supports E by means of the insulated bars M, the location of the eye-bolt N on the support E being adjusted to properly balance the device as a whole.

In Fig. 1, six electrodes are shown, although any number may, of course, be used. My invention is particularly adapted for use when multiphase currents are being delivered through the electrodes, or where several electrodes on each side of the electrical circuit are used for alternating or direct current.

As shown in Fig. 2, two similarly constructed clamping devices are shown as applied to the same electrode; but when desired, the second clamping device O may be omitted, as shown in Fig. 3. In use, for a single electrode, this clamp O, supported by the rope C', is provided with a support E', suspending tubes F', F' and separate current-conducting cables P connected to the source of electrical supply, and is movable with reference to the upper clamp. So arranged, one of the clamps is constantly connected to the current supply, while the other is disengaged to permit adjustment.

The operation of the device is as follows: When, owing to the waste at the lower end of the electrode, it becomes necessary to lower it and to change the position of the clamp, the motor, which normally holds the jaws in clamping engagement with the electrode, is operated to effect the withdrawal of the jaw G', thereby freeing the electrode. The clamp is then raised to some desired position higher up. The motor is then operated to again clamp the jaws against the

electrode. Even with electrodes of large size, as *e. g.*, twenty-four inches in diameter, this operation can be very rapidly effected, so that in cases where a number of electrodes are used, even though one electrode is momentarily disconnected, the electrical relations remain practically undisturbed.

While I have shown a fluid-operated cylinder for pneumatically or hydraulically actuating a piston, any other form of motor, such as one electrically or electro-magnetically energized, may be used. The advantage of such power-actuation of the motor lies not only in the great facility with which the clamps for these ponderous electrodes may be handled, but also in that it enables the operator to adjust the clamps from a point removed from the furnace, so that he is not subjected to the heat and fumes thereof,—the clamps in order to avoid waste of electric power in the electrodes themselves, being preferably located as close as possible to the furnace charge.

The mechanical details of the device as a whole, and particularly of the motor and its control, have *not* been illustrated in detail, as these are features within the knowledge and experience of those skilled in the art.

The clamping device may be used simply as a means for conveying current to an electrode which is separately supported, or may be itself used as both a suspending and contact-making device.

I claim:

1. In an electric furnace, the combination with an electrode, of a contact clamp, electrical connections to said clamp, a power-actuated device for operating said clamp,

and means, located at a distance from the 40 furnace, for controlling said power-actuated device.

2. In an electric furnace, the combination with an electrode, of a contact clamp, electrical connections to said clamp, and a fluid-pressure-actuated device for causing said clamp to engage with and disengage from said electrode.

3. In an electric furnace, the combination with an electrode, of a contact clamping-device, means for connecting said clamping-device to a source of current, and means comprising power-actuated clamp-operating devices for changing the position of the clamping-device without stopping the operation of the furnace.

4. In an electric furnace, the combination with an electrode, of a contact clamp and electrical connections thereto, said clamp comprising jaws adapted to engage the electrode, a motor connected to one of the jaws, and means for operating said motor.

5. In an electric furnace, the combination with an electrode, of a contact clamp comprising a supporting member, a frame having one end shaped to engage one portion of the electrode, a jaw shaped to fit another portion of the electrode, a motor carried by said frame and connected to said jaw, and means for supporting the frame and jaw from the supporting member.

In testimony whereof I affix my signature in presence of two witnesses.

JAMES G. MARSHALL.
